(57) **CLAIM**

An ornamental design for a tripod mounted hook, as shown and described.

DESCRIPTION

FIG. 1 is a perspective view showing the left side of our tripod mounted hook;

FIG. 2 is a perspective view showing the right side thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view showing the tripod mounted hook in an alternate position in which the arms have been repositioned relative to one another.
